[57] **CLAIM**

The ornamental design for a garment for female canines, as shown and described.

DESCRIPTION

FIG. 1 is a front elevational view of the garment for female canines, showing the new design;
FIG. 2 is a rear elevational view thereof;
FIG. 3 is a side elevational view thereof;
FIG. 4 is a top plan view thereof; and,
FIG. 5 is a bottom plan view thereof.
It is to be understood that the dashed lines in all the figures represent conventional stitching.
